DESIGN FOR A DINNER PLATE OR THE LIKE

Henry J. Davis, New York, N. Y.

Application September 11, 1945, Serial No. 122,014

Term of patent 7 years

(Cl. D44—15)

To all whom it may concern:

Be it known that I, Henry J. Davis, a citizen of the United States, residing at New York, in the county of New York and State of New York, have invented a new, original, and ornamental Design for Dinner Plates or the like, of which the following is a specification, reference being had to the accompanying drawing, forming a part thereof.

In the drawing:

Fig. 1 is a plan view of a plate showing my new design with two units of ornamentation shown completed.

Fig. 2 shows an enlarged view of a unit of ornamentation.

The units of ornamentation are repeated throughout the border of the plate as indicated by the dotted lines.

I claim:

The ornamental design for a dinner plate or the like, as shown and described.

HENRY J. DAVIS.
